his Attorney

UNITED STATES PATENT OFFICE.

JOHN JERMAIN PORTER, OF HAGERSTOWN, MARYLAND.

CHEMICAL APPLIANCE.

1,401,185.

Specification of Letters Patent. Patented Dec. 27, 1921.

Application filed December 3, 1919. Serial No. 342,140.

To all whom it may concern:

Be it known that I, JOHN J. PORTER, a citizen of the United States, residing at Hagerstown, county of Washington, State 5 of Maryland, have invented certain new and useful Improvements in Chemical Appliances; and I do hereby declare the following to be a full, clear, and exact description of the invention, such as will enable others 10 skilled in the art to which it appertains to make and use the same.

This invention relates to chemical appliances; and it has to do more particularly with chemical appliances useful for educational or entertainment purposes as a ready 15 means of demonstrating and controlling the interaction of selected chemical reagents on each other in water or other solution, usually but not necessarily in the presence of an 20 added indicator. One especially useful embodiment of the invention is a device of this general character which can be employed as a chemical toy to produce spectacular color 25 changes in a solution containing an indicator.

Generally described, the appliance forming the subject matter of the invention comprises a member provided with a plurality of reagent-holding means which are suitably 30 spaced apart and which are of such character that when exposed to liquid they will permit passage of liquid into and out of contact with the contained reagent. In general the reagents contained in these separ- 35 ate containers should be adapted to interact when brought together in aqueous solution, and most desirably such reagents should produce strikingly different color reactions either with or without special indi- 40 cators; so that when the containers are suc- cessively dipped into a solvent such as water, successive color changes are produced. For example, the member may be provided with two containers of the character described, 45 one holding a basic reagent and the other an acidic reagent. By manipulating the member in such manner as to dip the containers alternately into water containing phenolphthalein and properly stirring, the 50 solution can be made to change from pink or red to colorless, and back to pink or red, in accordance with the well known charac- teristics of this indicator. The appliance therefore serves as a convenient means of 55 demonstrating, for instructional purposes, the conduct of an indicator with different

reagents; or it may of course be employed to furnish spectacular effects in color changes for purposes of amusement and entertainment. The appliance therefore serves 60 both as an educational device and a fascinating toy.

While the device of the invention is susceptible of employment for useful and practical purposes, it is more particularly adapted 65 as before stated, for use as a chemical toy; and in order to afford a full understanding of the invention, an embodiment thereof in the form of what may be called a magic wand is hereinafter more particularly de- 70 scribed in detail for purposes of illustration. A magic wand embodying the principles of the invention is illustrated in the accompanying drawing which is a view in side elevation, parts being shown in section. 75

Referring to the drawing, 10 is a member, most desirably in the form of a rod of suitable material such as glass or the like, such rod in this instance being provided with terminal enlargements or knobs 11, 80 which may be provided for the purpose of more securely holding in place on the opposite ends of the rod, reagent-holding means comprising in this instance pieces of rubber tubing 12, said tubing being of quite 85 small internal diameter for best results. Each piece of tubing, being stretched to some extent where it passes over the knob on the corresponding end of the rod, is thus firmly secured to the rod frictionally. Each 90 piece of tubing extends sufficiently far beyond the corresponding end of the rod to provide a container for a lump or tablet of a solid soluble reagent which can be inserted into the open free end of the tube. 95 The wall of the container being elastic in this instance, the lump or tablet may be firmly held thereby even after a considerable portion of the reagent has been dissolved. It will be seen that the containers thus pro- 100 vided are liquid permeable by virtue of the small passage provided by the tubing bore which is open at the free end of each piece of tubing. In the present instance, the tablet 13 may be a basic reagent such as sodium 105 carbonate, for example; while the tablet 14 at the opposite end of the rod is an acidic reagent, such as acid sodium sulfate or the like. By inserting into water containing phenolphthalein that end of the rod or 110 magic wand carrying the tablet 13, and stirring, the solution will be turned from

colorless to pink or red, the depth of color depending principally upon the amount of indicator in the solution. By then reversing the rod and stirring with 5 the other end carrying the tablet of sodium bisulfate, the pink or red basic solution is neutralized and rendered colorless. These color reversals can be continued indefinitely, to the great amusement and wonderment of 10 children, and also for instruction in the underlying chemical principles involved.

With a device of the character described, many other reversible color reactions, involving the use of an indicator or not, may 15 evidently be carried out in an analogous manner; for instance, the iodin-thiosulfate reaction, with starch indicator, and the oxalic acid and permanganate reaction, without an indicator.

20 It is evident that many changes can be made in the form and details of the construction here illustrated for purposes of explanation, without departing from the spirit of the invention. For example, the 25 reagent containers may be of any other suitable character enabling chemical reagents to be held in the manner described and alternately or successively presented to a solution in the general manner described.

30 For example, instead of being made of rubber, the chemical-holding means may be made of any other suitable elastic or springy material that is sufficiently elastic to grip the lump of chemical matter and thus hold 35 it in proper position. Or the container may be a porous envelop or basket, formed of fabric, wire gauze, perforated metal or the like. The specific construction illustrated, in which small rubber tubing is employed for the containers, is especially advantageous, however, because of its simplicity and because of the ease with which 40 fresh tablets of chemicals can be inserted to replace those which have been exhausted, 45 In the particular embodiment of the invention, the tablets or pellets are shown as more or less conical in form to facilitate insertion of the containers; but while this has some practical advantages, it is in no sense 50 essential.

In its broader aspects, the invention is not limited to a unitary apparatus or appliance in which the several reagent-containers are supported upon a single holding member such as a rod or the like. That 55 is to say, the apparatus or appliance may comprise a set of two or more separate rods or other holding members, each provided with a reagent container for a reagent co-60 ordinated to the other reagent or reagents of the set and adapted to be employed alternately or successively as may be required to bring about the desired reaction or reactions. The means for supporting the separate reagent containers may therefore be

considered broadly as holding means, whether such means comprise a single member such as the rod here illustrated, or a plurality of separate members adapted to coöperate as a set, each member of a set 70 having mounted thereon a chemical coöordinated to the chemical mounted on the other member or members, such, for example, as a soluble acid reagent on one member, and a soluble basic reagent on another member, 75 the reagents being preferably in solid form.

What I claim is:

1. An appliance for inducing chemical and physical reactions which comprises a member provided at spaced localities with a plurality of receivers for separately holding different chemical reagents, such receivers being arranged to prevent the contents of one receiver from entering another receiver, each receiver being arranged to permit ingress and egress of liquid when exposed to the same. 80
2. An appliance for inducing chemical and physical reactions comprising a rod-like member provided near each end with means 90 adapted to hold a solid reagent while exposing the same to liquid into which said member may be dipped. 95
3. An appliance for inducing chemical and physical reactions comprising the combination, with a rod, of two pieces of rubber tubing mounted on opposite ends of said rod, each piece being open at its free end and extending beyond the corresponding end of the rod a sufficient distance to provide a 100 reagent receptacle. 105
4. The combination, with a member provided with a plurality of separate liquid-permeable containers, of different coöordinated chemical reagents in the respective 110 containers. 115
5. The combination, with a member provided with a plurality of separate liquid-permeable containers, of different chemical reagents in the respective containers, said reagents being adapted to produce different color reactions in solution. 120
6. The combination, with the appliance set forth in claim 3, of different coöordinated solid reagents contained in said receptacles, 115 said reagents being capable of interacting in solution. 125
7. The combination as set forth in claim 6, in which the solid reagents are, respectively, acidic and basic in character. 130
8. The combination with holding means, of a plurality of separate liquid-permeable containers supported thereby and adapted to contain different chemical reagents, the containers being arranged to prevent the contents of one container from entering another container. 135
9. Chemical magic apparatus comprising wand means supporting a plurality of separate non-communicating containers that are

- permeable by liquid and that are substantially the same in appearance and mounting, in combination with soluble chemical reagents contained in the respective containers and capable of reacting one upon another to produce color changes in a liquid into which said containers are successively dipped. 5
10. Chemical magic apparatus as set forth in claim 9, in which said containers are two in number and contain a solid acidic reagent and a solid basic reagent, respectively. 10
11. A chemical appliance, comprising the combination, with a common holder, of a plurality of coördinated chemicals mounted on said common holder and so spaced apart thereon as to be separately immersible in liquid. 15
12. A chemical appliance, comprising the combination, with a common holder, of a solid acid reagent and a solid basic reagent mounted on said common holder and so spaced apart thereon as to be separately immersible in liquid. 20
13. In a chemical appliance, a rod provided with a terminal knob in combination with an open tube of elastic material engaging the knob and extending somewhat beyond the knob for the reception of a hump of a solid reagent. 25
14. In a chemical appliance, a rod provided with a knob at each end in combination with a tube of elastic material extending somewhat beyond the knobs for the reception of lumps of solid reagents. 30
15. A chemical toy comprising a wand provided at each end with a liquid-permeable reagent receptacle. 35
16. A chemical toy comprising a wand provided at each end with a liquid-permeable reagent receptacle, in combination with a soluble solid acidic reagent contained in one receptacle, and a soluble solid basic reagent contained in the other. 40

In testimony whereof I hereunto affix my signature. 45

JOHN JERMAIN PORTER.
